PATENTED JUN 28 1870

SAMUEL MACFERRAN
DESIGN FOR
IRON RAILING.

WITNESSES INVENTOR

Thomas Kelly, Eliza Macferran

United States Patent Office.

ELHANAN OMENSETTER, OF PHILADELPHIA, PENNSYLVANIA, ASSIGNEE
TO SAMUEL MACFERRAN, OF SAME PLACE.

Design No. 4,192, dated June 28, 1870.

DESIGN FOR IRON RAILING.

The Schedule referred to in these Letters Patent and making part of the same

I, ELHANAN OMENSETTER, of the city of Philadelphia, and State of Pennsylvania, have invented and produced a new and original Design for Iron Railing, of which the following is a specification.

The nature of my design is fully represented in the accompanying photographic illustration, to which reference is made.

The photograph represents a side elevation of a panel of a fence, composed of longitudinal ribs A A' and open pales B.

Around the pales B is a running vine, C, the leaves of which, at the connection of the rods with the rails A', are duplex, and spread over the rails.

The rails A A' have ornamental bands, b, at the ends and between the pales B.

I claim as my invention—

The design for iron railing, as shown.

In testimony that the above is my invention I have hereunto set my hand and affixed my seal to this 23d day of April, 1870.

ELHANAN OMENSETTER. [L. S.]
